UNITED STATES PATENT OFFICE.

EDWARD HART, OF EASTON, PENNSYLVANIA.

CHEMICAL APPARATUS.

1,293,423.

Specification of Letters Patent.

Patented Feb. 4, 1919.

Application filed September 24, 1918. Serial No. 255,443.

To all whom it may concern:

Be it known that I, EDWARD HART, a citizen of the United States, residing at Easton, in the county of Northampton and State of Pennsylvania, have invented certain new and useful Improvements in Chemical Apparatus, of which the following is a full, clear, and exact description.

This invention relates to chemical apparatus for weighing, absorbing, washing, or for otherwise treating gases by passing the same through and in intimate contact with a liquid or solid, and its chief object is to provide an improved apparatus for the purpose, of simple character, which can be readily manipulated and can be easily cleaned and charged. To this and other ends the invention consists in the novel features hereinafter described.

20 In its preferred form the invention comprises a "bottle," preferably of glass, having a wide mouth to permit easy introduction of large solids, as for example large glass beads or balls such as are used for the purpose of carrying a film of reagent, say sulfuric acid, so as to expose a large area to the current of gas, or for the purpose of breaking up the current into tortuous streams. The gas is introduced through a 25 tube connected to the lower portion of the bottle, and passes out through a tube connected with the upper portion, preferably the neck. The two tubes are connected to the same valve cock, so that both the inlet 30 and the outlet are closed simultaneously and opened simultaneously.

The embodiment thus briefly outlined is illustrated in the accompanying drawings, in which the figure shows the apparatus in 35 vertical section.

The vessel or bottle is designated by A, and is provided with a neck B, preferably wide, so as to permit filling with solid bodies of rather large size when desired. The outlet 40 tube C extends from the neck of the bottle, and the hollow stopper D has a lateral aperture E which by a slight turn of the stopper may be carried out of or into register with the orifice of the outlet tube. The 45 inlet tube F opens into the lower part of the bottle, and both tubes extend into connection with a valve or cock having a plug G. The latter is integral with the tube H and has an angular passage I extending 50 from the end of tube H into position for register with the tube F; and the tapered

shell J, in which the plug G turns, is integral with tube K. The plug G also has an angular passage L extending from the tube K to a point where it will register with tube C when passage I is in registry with tube F. The gas to be treated is delivered to the tube H by means of rubber tubing slipped over the end of the tube, and the residuum, if any, is carried away by like 55 tubing fitted on the end of tube K.

It will be observed that a turn of the plug G closes or opens both the inlet tube F and the outlet tube C. Preferably the passages I and L, are of such size that not more than 60 a quarter turn of the cock is sufficient to open or close the tubes. A slight turn (say a quarter) of the stopper D closes the outlet tube only, as may be desirable when a pressure is to be produced in the bottle. 75

The apparatus illustrated is designed particularly for absorbing carbon dioxide or other acid gas and determining its amount, but of course can be used for other purposes as well, as for example for washing. In the 70 former case the bottle is charged with suitable absorbent, and is weighed with its contents. The gas is then passed through, and the bottle and contents weighed again. The increase in weight then gives the 85 amount of gas absorbed.

The valve plug G being removable as readily as the stopper D, the apparatus is easily cleaned and rinsed.

It is to be understood that the invention 90 is not limited to the apparatus herein specifically illustrated but can be embodied in other forms without departure from its spirit as defined by the following claims.

I claim:

1. An apparatus for gas-absorption and other purposes, comprising a vessel having a removable closure, gas inlet and outlet tubes connected to the lower and upper portions of the vessel respectively, and a 100 single valve connected to both tubes independently of the closure, to control both tubes simultaneously.

2. An apparatus for gas-absorption and other purposes, comprising a vessel having 105 in its upper portion a seat for a closure, a gas outlet tube extending from said seat, a rotatable and removable closure mounted in said seat and having an outlet aperture adapted to be carried into and out of register with said outlet tube by rotating the closure, a gas inlet tube connected with the 110

lower portion of the vessel, and means for delivering gas to the inlet tube and carrying gas away from the outlet tube, said means including a single valve controlling both tubes.

5 An apparatus for gas-absorption and other purposes, comprising a vessel having a neck B at its top, a gas outlet tube C leading laterally from the neck, a rotatable closure D seated in the neck and having an outlet aperture E adapted to be carried into and out of registry with said outlet tube by rotating the closure, a gas inlet tube F connected to the lower portion of the vessel, a 10 valve shell J connected to the gas inlet and

outlet tubes and having an axial discharge tube K, and a valve-plug G rotatable in the shell and having a gas-delivery tube H and provided with a passage I leading from the said delivery tube into position for registry with the said inlet tube and a passage L extending from a position for registry with the said outlet tube into registry with the said discharge tube, whereby rotation of the plug controls both the inlet and the outlet tube simultaneously. 20 25

In testimony whereof I hereunto affix my signature.

EDWARD HART.
